UNITED STATES PATENT OFFICE.

EDGAR C. WORTHEN, OF CHARLOTTE, NORTH CAROLINA, ASSIGNOR TO
WILLIAM C. MORGAN, OF SAME PLACE.

GEARING FOR CHANGING SPEED.

SPECIFICATION forming part of Letters Patent No. 278,070, dated May 22, 1883.

Application filed April 16, 1883. (No model.)

To all whom it may concern:

Be it known that I, EDGAR C. WORTHEN, of Charlotte, county of Mecklenburg, State of North Carolina, have invented a new and useful Improvement in Gearing for Changing Speed, of which the following is a full, clear, and exact description, reference being had to the accompanying drawings, making part of this specification.

10 My invention relates to a novel arrangement of gearing, whereby the speed of the same and of the shafting actuated thereby may be easily and quickly regulated or changed to suit the class of work which it is desired to perform or 15 the machine to which said improved arrangement of gearing is attached, and it may be applied to hay, cotton, or rag presses, lathes, or almost any machine where it is desired to change the speed of rotation of the driving- 20 shaft.

It consists in the employment of a driving-wheel provided with a pinion permanently attached to it, mounted loosely on its shaft, and engaging with a gear-wheel mounted loosely 25 on a secondary shaft, said shafts being provided with intermeshing gear-wheels keyed to them, in combination with clutches, whereby said drive-wheel is adapted to actuate its shaft directly or to be indirectly connected therewith 30 for driving it through its pinion and the intermeshing gears on the driving and secondary shafts; also, in a novel arrangement of clutches on the driving and secondary shafts, and of the pivoted lever actuating said clutches, as 35 hereinafter described.

The accompanying drawing is a plan view, showing the arrangement of the gearing and the pivoted lever and clutches.

40 A represents the main driving-shaft of the machine, to which my improvement is applied, and B is a secondary shaft arranged and rotating in line parallel therewith.

45 C is a driving-pulley mounted loosely on the shaft A, for a purpose hereinafter set forth. To this pulley is rigidly attached a spur-pinion, D, also loose on the shaft, and provided with a clutch-face, D', adapted to receive a corresponding clutch, I, for engaging said pulley and pinion with the shaft A. On the opposite side 50 of pulley C from that to which the spur-pinion D

is secured, but detached from it, another gear-wheel, G, is provided, keyed to the shaft A in any suitable manner, and always rotating therewith. The wheel G engages with another wheel, F, preferably of smaller diameter, on 55 the secondary shaft B, as shown, said wheel F being also keyed to its shaft, adapting it to rotate therewith. On the secondary shaft B, and engaging with the pinion D, is a fourth gear-wheel, E, mounted loosely on its shaft, 60 and provided with a clutch-face, E', adapted to receive a clutch, H, for engaging it with shaft B, as shown.

H and I are clutches of the ordinary form and construction, being feathered to the shafts 65 on which they are mounted and rotating therewith, adapting them to slide upon said shafts, and by their engagement with the clutch-faces E' and D' to throw the wheels E and D, respectively, into action. As one only of said 70 clutches is intended to be employed at one time, it is thought best to so arrange them in connection with their rocking lever that when either one of them is engaged with its corresponding wheel the other will be thrown entirely out of engagement. For this purpose I 75 find that the use of a common lever, K, for actuating both clutches, pivoted intermediate of said clutches, and provided with forks or arms fitting in grooves *h* and *i*, is very convenient and effective, for by rocking lever K upon its pivot L the same movement that causes the engagement of one clutch with its gear removes the other of said clutches from engagement with its gear.

Having explained the use of lever K and its clutches, I now proceed to show the operation of the gear-wheels, whereby the change of speed of rotation of the shaft A is obtained.

It will be seen that by vibrating lever K outward, and thereby throwing clutch I into action, the driving-pulley C and its attached pinion will engage the main driving-shaft A, and the latter will be rotated with a speed equal to the speed of rotation of the driving-pulley. 90 The wheel E engaging with the pinion D, in that case being idle, will produce no result, but merely revolve around the shaft B as it is actuated by the pinion D. By rocking lever K in the other direction, or toward the wheel E, 95 100

and thus throwing clutch H into action, wheel E will engage the secondary shaft B, and, being in engagement with the pinion D, will in turn cause the rotation of shaft B. As the wheel F is keyed to the secondary shaft B, the revolution of said shaft will effect the revolution of wheel F, and the latter being in engagement with wheel G, before referred to as keyed to shaft A, the shaft A will be driven through such engagement, and as the result of the arrangement of the gearing, driving from small to large wheels, a materially-slower revolution of shaft A will be produced.

It is apparent that the arrangement of the gearing may be varied to suit the requirements of the machine to which it is desired to apply it—as, for instance, instead of gearing down from high to low speed, as described and illustrated, it may be desirable to gear up from low to high speed, which may be done by reversing the order and arrangement of the gear-wheels. Therefore I do not limit myself to the particular arrangement shown and described. Friction wheels or gears may be substituted for those shown and described, and also friction or other suitable forms of clutches may be employed in lieu of the clutches shown. Motion may be imparted to pulley C from any suitable motor.

Having now described my invention, what I claim as new is—

1. Parallel shafts with intermeshing gears fast thereon and intermeshing gears loose

thereon, of unequal diameters, in combination with adjustable clutches feathered to and sliding upon said shafts, for engaging one or the other of the loose gears with its shaft for changing the speed of the driving-shaft, substantially as described.

2. The shaft A, having the gear-wheel G fast upon it, in combination with the pulley C, loose on said shaft A, and having the pinion D rigidly connected with it, and the gear-wheels E and F on a secondary shaft, B, arranged and operating substantially as described.

3. The shaft A, having the gear-wheel G fast upon it, the driving-wheel having the pinion D rigidly connected with it, loose on said shaft A, and the gear-wheels E and F on a secondary shaft, B, in combination with the clutches H and I, for throwing the wheels E and D into engagement with their respective shafts, substantially as and for the purpose described.

4. The gears E and D, mounted loosely on their shafts, in combination with clutches feathered to and sliding upon said shafts, and the shifting-lever pivoted at a point intermediate of said clutches, and adapted to operate them simultaneously, substantially as described.

In testimony whereof I have hereunto set my hand this 13th day of April, A. D. 1883.

EDGAR C. WORTHEN.
